REVOLVING BOOK SHELF

Roy E. Elvers, Los Angeles, Calif.

Application November 29, 1943, Serial No. 512,129

4 Claims. (Cl. 45—60)

My invention relates to a revolving book shelf and has for its principal object, to provide a simple, compact and easily operated shelf or support mounted to rotate on a horizontal axis and which may be readily swung from one position to another so as to bring the desired book or books into convenient position for use.

Further objects of my invention are, to provide a revolving book shelf of the character referred to having simple and efficient means for detachably mounting books and the like on opposite sides of the shelf, and to provide means which act automatically for engaging the edges of the revolving shelf and holding same in position for use.

With the foregoing and other objects in view, my invention consists in certain novel features of construction and arrangement of parts which will be hereinafter more fully described and claimed and illustrated in the accompanying drawing in which:

Fig. 1 is a side elevational view of a revolving book shelf embodying my invention.

Fig. 2 is an end view.

Fig. 3 is an enlarged sectional view taken on the line 3—3 of Fig. 1.

Fig. 4 is a horizontal section taken on the line 4—4 of Fig. 3.

Fig. 5 is an enlarged section taken on the line 5—5 of Fig. 3.

Fig. 6 is an enlarged section taken on the line 6—6 of Fig. 2.

Fig. 7 is a cross section taken on the line 7—7 of Fig. 6.

Fig. 8 is a perspective view of one of the devices utilized for detachably connecting the books on the shelf.

Referring by numerals to the accompanying drawing which illustrates a preferred embodiment of my invention, 10 designates a suitable base which may be a book rack, filing cabinet or the like, and secured thereto, are spaced upwardly projecting posts 11.

Mounted to rotate on a horizontal axis between posts 11 is a shelf or supporting member 12, preferably rectangular in shape and formed of wood, metal or plastics.

Suitably secured to the intermediate portion of the side edges of the shelf, are metal straps 13, the outer faces of which lie flush with the outer faces of the shelf and projecting outwardly from the central portion of the sides of said straps, are short arms 14.

Formed in the upper portions of legs 11 are apertures 15 and secured to the inner faces of

said legs and overlying said apertures are metal plates 16.

Passing through apertures 15, are the outer portions of screws 17 which pass through plates 16 and through apertures in straps 13 with the threaded portions of said screws seated in shelf 12.

Thus, the screws provide a horizontal axis for the shelf and to provide a certain amount of friction between plates 16 and straps 13, small expansive coil springs 18 are arranged between the heads of screws 17 and plates 16. (See Fig. 6.)

To retain the shelf in a horizontal position 15 while in use, I utilize conventional cupboard door catches 19, seated in legs 11, to the sides of apertures 15, which catches include spring pressed balls or plungers 20 adapted to enter countersunk apertures 21 formed in straps 13, 20 when the shelf occupies a horizontal plane.

The edges of the straps 13 adjacent the catches just described, are bevelled as designated 21a in order to enable the spring pressed balls to ride onto the outer face of said straps.

Obviously any other suitable and convenient form of shelf holding means may be utilized instead of the form herein shown and described.

The means utilized for detachably mounting the books, catalogues and the like to the revolving shelf include small metal rods 22, about the size of the spokes in a bicycle wheel, which rods extend lengthwise through the central portion of the book adjacent the back binding thereof, as illustrated in Fig. 8 with the ends of said rods 30 projecting short distances for rotary engagement in apertures 23 formed in the outer portions of arms 14.

To detachably connect the rods 22 to the book or catalogue, clips formed of resilient metal, preferably steel, have their central portions bent to form loops 24, with the end portions of the wire, crossing each other and bent into planes at right angles to the loops to provide curved legs 25.

When these clips are applied to the ends of the book backs, the legs 25 overlie the ends of the books adjacent the backs as seen in Fig. 8 and as the normal tendency of the loop 24 is to expand and thereby cause legs to move toward each other, said legs grip the projecting ends of rod 22, thereby holding same in the book.

While not in use, the shelf occupies a vertical position between the posts 11, due to the weight of the books carried by said shelf, which books 55 hang from the arms 14, immediately adjacent

the lower portion of the shelf. (See Figs. 1 and 2).

In the use of the shelf, the same is normally engaged and swung into a horizontal plane, thereby bringing the desired book onto the upper face of the shelf, and when so positioned the balls 20 of the catches 19 engage in apertures 21 in straps 13, thus holding said shelf in position for use.

To return the shelf to its normal position, it is only necessary to engage either end thereof and swing same a sufficient distance to disengage the balls 20 from aperture 21a, whereupon the weight of the books will swing said shelf to vertical position.

Instead of being mounted on a cabinet, case or the like the support or supports for the revolving shelf may be fixed or hinged to a suitable upright support such as a wall, partition or door frame, thus conserving floor space, and when hinged, the shelf while not in use, may occupy 15 an out of the way position.

Thus it will be seen that I have provided a revolving shelf which is simple in structure, inexpensive of manufacture and very effective in performing the functions for which it is intended.

It will be understood that minor changes in the size, form and construction of the various parts of my improved revolving shelf may be made and substituted for those herein shown and described without departing from the spirit of the invention, the scope of which is set forth in the appended claims.

I claim as my invention:

1. In a revolving book shelf, a pair of spaced supports, a shelf mounted to rotate on a horizontal axis between said supports readily releasable means for holding said shelf in horizontal position and means for suspending books on the sides of said shelf from points near the horizontal plane occupied by its axis which suspending means comprises plates secured to the sides of said shelf adjacent the axis thereof, ears projecting from the opposite edges of said plates and book engaging rods having their ends removably seated in said ears.

2. In a revolving book shelf, a pair of spaced supports, a shelf mounted to rotate on a horizontal axis between said supports, means for suspending books on the sides of said shelf from points near the horizontal plane occupied by said axis, which suspending means comprises plates secured to the sides of said shelf adjacent the axis thereof, ears projecting from the opposite edges of said plates and book engaging rods having their ends removably seated in said ears and detent means seated in said supports for engaging said plates and holding said shelf in a horizontal position.

3. A revolving shelf as set forth in claim 2 including means for producing varying degrees of friction between said shelf and its supports.

4. A revolving shelf as set forth in claim 2 including resilient book engaging clips removably applied to the ends of said rods.

ROY E. ELVERS.
